UNITED STATES PATENT OFFICE.

HARRY SWINGLEHURST, OF BOSTON, MASSACHUSETTS, ASSIGNEE TO SCOTT & WILLIAMS, INCORPORATED, OF PHILADELPHIA, PENNSYLVANIA, A CORPORATION OF NEW JERSEY.

KNITTING-MACHINE.

1,143,263.

Specification of Letters Patent. Patented July 27, 1915.

Application filed May 26, 1911. Serial No. 629,668.

To all whom it may concern:

Be it known that I, HARRY SWINGLEHURST, a citizen of the United States, residing in Boston, Massachusetts, have invented 5 certain Improvements in Knitting-Machines, of which the following is a specification.

The object of my invention is to provide means for retaining the needles and jacks of a circular knitting machine in proper 10 relation to one another, my invention having special significance in connection with machines employing bearded needles such as shown in applications for patent filed by Robert W. Scott on March 17, 1911, Serial 15 Numbers 615,163 and 615,164, and in application for patent filed by myself upon the third day of May, 1911, Serial No. 624,801.

In the accompanying drawing—Figure 1 is a vertical sectional view of a knitting machine cylinder having needles, jacks and a retaining device therefor constructed in accordance with my present invention and Fig. 2 is a top or plan view of said retainer.

In machines of the class recited the needles are operated through the agency of a 20 jack, and in the drawings the jack illustrated is similar to that employed in machines of the type shown in George D. Mayo's Patent 726,178, dated April 21, 1903.

In the drawing, 1 represents the needle cylinder, 2 the needle jack, and 3 the needle, said needle and jack being locked together by engagement of the butt 4 of the needle with appropriate jaws formed by the enlarged head 5 of the jack.

In practice difficulty has been experienced in preventing the head of the jack from leaving the butt of the needle, even when coiled springs have been applied, this tendency to withdraw the jaws of the jack from engagement with the butt of the needle being due to the downward pressure of the knitting cams upon the relatively long butt 7 of the needle jack.

It is also customary, in machines of this class, to provide one or more spring bands, in order to retain the needles in their 45 grooves, but in developing a machine in which the bearded end of the needle shank is offset outwardly, as shown and described in the applications above referred to, it has been found that when the needles are rendered inactive by being abnormally elevated the spring band tends to hold the

needle inwardly and thereby prevent any 55 outward yield of the shank or stem of the elevated needle, and when the last needle of the inactive set is thus prevented from yielding outwardly the tendency is to cause a slack stitch at the gore, in view of the fact 60 that the knocking-over portion of the first adjacent active needle is in a different plane from the main stem of the last inactive needle.

In order to overcome these difficulties I 65 have provided the needle cylinder with an encircling ring 10, of such dimensions that its inner face contacts with the heads 5 of the jacks 2, as shown in Fig. 1, and effectively prevents them from leaving the butts 70 of the needles.

The upper edge of the ring 10 is provided with an inwardly projecting flange 11 which rests upon the upper ends of the ribs or partitions 12 between which the needles and 75 jacks are guided in their reciprocation, the inner periphery of this flange preventing any abnormal outward movement of the needle but enough space being provided between said inner periphery and the stem of 80 the needle to permit slight outward movement of the stem of an elevated and inactive needle, whereby the latter may move toward or into register with the projected upper portion of the stem of an adjoining active 85 needle, thereby overcoming the tendency to cause slack stitches at the gore, to which I have above referred.

The ring 10 is split in order to permit of its ready removal from or application to the 90 machine, the sections of the ring being held together by plates 13, as shown in Fig. 2, and at one side of the ring the ends are separated from each other to a slight extent so as to provide a gate 14 and thus permit 95 ready removal or insertion of the needles and jacks. The ring has the further advantage of protecting the needles and jacks from accumulations of dirt or lint.

I claim:

1. The combination, in a knitting machine, of needles having stems which are forwardly bent and bearded at their upper ends, jacks having heads engaging butts at the lower ends of said stems and permitting 105 a limited amount of rocking movement of the needle in respect to the jack, and a cylinder having a retaining ring with rigid

inner face for engaging the jacks and retaining them in engagement with the needles and another ring with rigid inner face bearing such relation to the lower portions of the stems of the needles as to retain the same closely against the cylinder when the needles are knitting, but when a needle is raised out of operative position permitting the straight portion of the needle stem of the end needle 10 of the raised or inoperative set to be moved out into line with the forwardly bent upper portion of the stem of the adjoining active needle.

2. A knitting machine having needles with 15 loosely attached jacks, a cylinder in which said needles and jacks are mounted, and a

retaining ring for said needles and jacks, said ring being split and providing between adjoining ends of its members a space bridged by an outer plate connecting said 20 members, said space providing a gate for the insertion and removal of the needles and jacks without removing said connecting plate.

In testimony whereof, I have signed my 25 name to this specification, in the presence of two subscribing witnesses.

HARRY SWINGLEHURST.
